UNITED STATES PATENT OFFICE.

LÉON GAUMONT, OF PARIS, FRANCE, ASSIGNOR, BY MESNE ASSIGNMENTS, TO EASTMAN KODAK COMPANY, OF ROCHESTER, NEW YORK, A CORPORATION OF NEW YORK.

CINEMATOGRAPH FOR PROJECTION IN NATURAL COLORS BY THE THREE-COLORS PROCESS.

1,233,772.

Specification of Letters Patent. Patented Jan 17, 1917.

Application filed November 12, 1913. Serial No. 800,546.

To whom it may concern:

Be it known that I, LÉON GAUMONT, a citizen of the Republic of France, residing in Paris, France, have invented certain new and useful Improvements in Cinematographs for Projection in Natural Colors by the Three-Colors Process, of which the following is a specification.

In my application for patent of the United States filed 5th February 1912, Serial No. 675627, I have described a device for regulating objectives permitting, when the latter have been displaced simultaneously until the central image is clear, of displacing individually, along their axes, the extreme objectives by means of movable nuts until the images furnished by the three objectives are clear and equal in size.

The present improvement relates to a modification of this device permitting of producing the advancing or retreating movement of each of the extreme objectives by the mere operation of a lateral knob.

The following description with the aid of the drawings shown by way of example will furnish an understanding of the object and the advantages of this modification.

Figure 1 is a longitudinal section through the frame of the objectives O' , O^2 , O^3 , at the level of the axis of one of the knobs.

Fig. 2 is a vertical section through the axes of two knobs.

In said drawings letter g designates the lens-frames, d the lens-frame-supports in which the extreme lens-frames are longitudinally adjustable, and W a support for the lens-frame-support in which the lens-frame supports d are mounted. The lens-frame supports d are adjustable in the support W for the lens-frame supports around the pivot w by means of thumb screws v , and also are adjustable on the pivot w around an axis perpendicular to the plane of Fig. 1, by means of the thumb-screws s .

To each knob B , a spindle t is secured, which is terminated by an eccentric cam C located in the recess e' of the lens-frame carrying an objective. By turning a knob B a longitudinal movement of the corresponding lens frame g is produced, either forward or backward.

To place each lens frame in its lens frame support d or to withdraw it therefrom with-

out the cam C being an obstacle, this cam is removed by bringing it into the recess a formed in the said lens frame, by exerting a tractive effort on the knob B . A helical spring r placed around the rod t and bearing with one end on the cam and with the other on a member integral with the lens frame support, enables the cam to return automatically to its recess e' in the lens-frame when this recess confronts the cam located in the recess a , as the lens-frame is slid in.

In order that the lens-frame may be turned over, a symmetrical recess e^2 has been formed on the other side of the lens-frame.

What is claimed is:

1. In a photographic apparatus, a lens-frame, and adjusting means therefor, comprising a cam, said frame having a recess for engagement with said cam, and said cam being movable into and out of said recess to permit removal of said frame.

2. In a photographic apparatus, a support, a lens-frame removably mounted in said support, and adjusting means therefor, comprising a cam, said frame having a recess for engagement with said cam, and said cam being movable into and out of said recess to permit removal of said frame.

3. In a photographic apparatus, a lens-frame, and adjusting means therefor, comprising a cam, said frame having a recess for engagement with said cam, and said cam being movable into and out of said recess to permit removal of said frame, and a means for pressing said cam into engagement with said recess.

4. In a photographic apparatus, a support, a plurality of lens-frames, one of which is removably mounted in said support, and adjusting means for one of the lens-frames comprising a cam, said frame having a recess for engagement with said cam, and said cam being movable into and out of said recess to permit removal of said removable lens-frame.

5. In a photographic apparatus, a support, a plurality of lens-frames, a plurality of which are removably mounted in said support, and adjusting means for a plurality of said lens-frames, each comprising a cam, said frames each having a cam recess,

and each of said cams being movable into and out of said recesses to permit removal of said removable lens-frames.

6. In a photographic apparatus, a lens-frame, a lens-frame-support, and a support for said lens-frame-support, said lens-frame-support being adjustable in its support on a vertical and a horizontal axis, and said lens-frame being axially adjustable in said lens-frame-support, and means for adjusting said lens-frame, said means being carried by said lens-frame-support.

7. In a photographic apparatus, a lens-frame, a lens-frame-support, and a support for said lens-frame-support, said lens-frame-support being adjustable in its support on a vertical and a horizontal axis, and said lens-frame being axially adjustable in said lens-frame-support, and means for adjusting said lens-frame, said means being carried by said lens-frame-support, said adjusting means comprising a cam.

8. In a photographic apparatus, a lens-frame, a lens-frame-support, and a support for said lens-frame-support, said lens-frame-support being adjustable in its support on a vertical and a horizontal axis, and said lens-frame being axially adjustable in said lens-frame-support, and means for adjusting said lens-frame, said means being carried by said lens-frame-support, said adjusting means comprising a cam and said cam being disengageable from said lens-frame for permitting removal of the latter.

9. In a photographic apparatus, a plurality of lenses in close proximity to one another, one of which is mounted in an independently movable lens-frame, a lens-frame-support, and a support for said lens-frame-support and other of the lenses, said lens-frame-support being adjustable in its support on a transverse axis, and said lens-frame being axially adjustable in said lens-frame-support.

10. In a photographic apparatus, a plurality of lenses in close proximity to one another, one of which is mounted in an independently movable lens-frame, a lens-frame-support and a support for said lens-frame-support and other of the lenses, said lens-frame-support being adjustable in its support on a transverse axis, and said lens-

frame being axially adjustable in said lens-frame-support, and means for adjusting said lens-frame, said means being carried by 55 said lens-frame-support.

11. In a photographic apparatus, a plurality of lenses in close proximity to one another, a plurality of lens-frames in which said lenses are mounted, a plurality of lens-frame-supports, and a support for said lens-frame-supports, said lens-frames being axially adjustable in said lens-frame-supports.

12. In a photographic apparatus, a plurality of lenses in close proximity to one another, a plurality of lens-frames in which said lenses are mounted, a plurality of lens-frame-supports, and a support for said lens-frame-supports, said lens-frames being axially adjustable in said lens-frame-supports, 70 and means for adjusting said lens-frames, said means being carried by said lens-frame-supports.

13. In a photographic apparatus, a plurality of lenses in close proximity to one another, a plurality of lens-frames in which said lenses are mounted, a plurality of lens-frame-supports, and a support for said lens-frame-supports, said lens-frame-supports being adjustable on transverse axes therein, 80 said lens-frames being axially adjustable in said lens-frame-supports, and means for adjusting said lens-frames, said means being carried by said lens-frame-supports, and being movable independently of said support 85 for said lens-frame-supports.

14. In a cinematographic apparatus operating upon the three-color principle, the combination of three objective frames, two of which are adjustable, and adjusting 90 means comprising for each objective a cam, said adjustable frames having recesses for engagement with said cams, said cams being movable into and out of said recesses to permit removal of the frames, and springs for 95 pressing said cams into engagement with said recesses.

In witness whereof, I have hereunto signed my name in the presence of two subscribing witnesses.

LÉON GAUMONT.
